Patented Nov. 14, 1922.

Inventor

Henry F. Tiedemann
By his Attorney Joseph L. Levy

UNITED STATES PATENT OFFICE.

HENRY F. TIEDEMANN, OF NEW YORK, N. Y., ASSIGNOR TO THEO. TIEDEMANN & SONS, INC., OF NEW YORK, N. Y., A CORPORATION OF NEW YORK.

BOX FOR GARMENTS.

Application filed September 12, 1922. Serial No. 587,692.

To all whom it may concern:

Be it known that I, HENRY F. TIEDEMANN, a citizen of the United States, and a resident of the city, county, and State of New York, have invented a certain new and useful Improvement in Boxes for Garments, of which the following is a specification.

My invention relates to a box or receptacle adapted to be used for containing articles of wearing apparel and particularly suits of clothing, dresses, coats, waists, burial shrouds or like articles.

An object of this invention is to provide a box of this character for holding such articles and displaying them in such a manner as to show the garment as it appears when in use, and permitting a box of comparatively small capacity to be used for a garment.

20 A further object of this invention is to provide a garment box with suitable means for retaining the garment within the box in such a manner as to prevent undue creasing or folding of the garment, yet which will allow the garment to be readily removed from the box for the purpose of display and replaced within the box in its former position.

One of the difficulties had with garments held in a folded position in a box, is the formation of a transverse fold or crease in the garment, particularly when the garment is made of a thin material and when it is retained in the box in a folded position for any length of time. A still further object therefore, of this invention, is to provide means within a box for retaining a garment therein in a folded position without the possibility of folds or creases being formed in the garment.

These and other objects are accomplished by my invention, a more particular description of which will appear hereinafter.

Reference is to be had to the accompanying drawing, forming a part hereof, in which—

Figure 1 is a perspective view of the box tray;

Figure 2 is a longitudinal sectional view 50 of the box and its contents, and

Figure 3 is a plan view of the box and its contents, with the cover removed, and parts being broken away to disclose construction.

Throughout the various views of the drawings, similar reference characters designate similar parts.

In the preferred embodiment of my invention, as disclosed in the accompanying drawing, the box is shown provided with a bottom 1, longitudinal sides 2 and ends 3 and 4. The upper edge of the box is reinforced by means of a strip 5 secured on the inner face of the box along the edge. The box may be of any desired shape or form 60 to accommodate the contents, and the box herein shown is of a substantially rectangular form and comparatively shallow in depth. A cover, hinged or otherwise, may be provided.

At 6 is shown the garment adapted to be held by the box. The garment herein disclosed is a burial shroud, but it will be obvious that any garment may be retained within the box in a similar manner. The 75 garment in this instance, is, when in its normal position, longer than the box, and in order to properly fit therein, is doubled or folded transversely as at 7, the fold being located at 7 adjacent the end 3 of the 80 box.

The upper end of the garment is received upon a hanger 8 provided with a hook 9 which engages with a spring hook 10 which is secured in a portion of the wooden frame 85 5. The hook 10 extends downwardly into the box and parallel to the end 4 thereof.

As heretofore stated, the hook 10 is of spring material so that when it is engaged with the hook 9 on the hanger inadvertent 90 disengagement of the hooks is unlikely.

At 11 is shown the garment-retaining member which is in the nature of a flat tray having a bottom 12 and upwardly-extending sides 13. These two longitudinal sides 13 are 95 connected at one end by a rod 14 over which the garment is folded on the line 7. The bottom 12 of the tray terminates a distance from the rod so that the under fold of the garment extends gradually up towards the rod 14, over the same and has its upper portion lying flat upon the bottom of the tray. (See Figure 2.) To retain the tray within the box, portions of the sides 13 located opposite to the rod 14 are cut away 105 to provide shoulder portions 15 which project below the frame 5 at the end 4 of the box. This arrangement holds one end of the

tray within the box, the other end being held in position by pressure of the cover of the box.

To remove the garment from the box, the 5 hook 9 is disengaged from the hook 10, and the end of the tray at which the rod 14 is located, is lifted and the tray and garment may be lifted out of the box.

From the foregoing, it is obvious that my 10 invention is not to be restricted to the exact embodiment shown, but is broad enough to cover all structures coming within the scope of the annexed claims.

What I claim is:—

15 1. An article of the class described comprising a box for containing a garment in a folded condition, a tray in said box having a bottom adapted to lie between the folds of the garment, said tray having a pair of upwardly projecting side members, and a rod 20 connecting said side members at one end thereof.

2. An article of the class described comprising a box, a tray adapted to fit therein, said tray having a pair of upwardly extending longitudinal sides, said sides projecting beyond the bottom of the tray at one end thereof, and a rod extending between and connecting said projecting portions of the sides. 25

3. An article of the class described comprising a box adapted to contain a garment in folded condition, a tray adapted to lie between the folds of said garment, said tray having a bottom and a pair of side members 30 extending upwardly therefrom, a rod connecting said side members at one end with portions of said side members cut away at the opposite end to form shoulders adapted to lie under portions of the box. 35

Signed at the city, county and State of New York, this 7th day of September, 1922. 40

HENRY F. TIEDEMANN.
